UNITED STATES PATENT OFFICE.

WILLIAM A. ELLIOT, OF YONKERS, NEW YORK.

DESIGN FOR CARPET.

41,014.

Specification for Design.

Patented Nov. 29, 1910.

Application filed October 10, 1910. Serial No. 586,400. Term of patent 7 years.

To all whom it may concern:

Be it known that I, WILLIAM A. ELLIOT, a citizen of the United States, residing at 264½ Woodworth avenue, city of Yonkers, and State of New York, have invented a new, original, and ornamental Design for Carpets, of which the following is a specification, reference being had to the accompanying drawing, forming part thereof.

The figure is a plan view of a portion of a carpet, showing my new design.

I claim:

The ornamental design for a carpet, as shown.

WILLIAM A. ELLIOT.
